UNITED STATES PATENT OFFICE.

HERBERT G. STREAT, OF NEW YORK, N. Y.

BICYCLE-CRATE.

SPECIFICATION forming part of Letters Patent No. 555,833, dated March 3, 1896.

Application filed September 4, 1895. Serial No. 561,412. (No model.)

To all whom it may concern:

Be it known that I, HERBERT G. STREAT, a citizen of the United States, residing at New York, in the county and State of New York, 5 have invented certain new and useful Improvements in Bicycle-Crates, of which the following is a specification, reference being had to the drawings accompanying and forming a part of the same.

10 The present extended use of bicycles and their frequent shipment by rail or boat between distant points visited by their owners involve considerable difficulty, annoyance, and expense in providing suitable cases or 15 crates for their protection in transit; but, so far as I am aware, there is no device known or used for this purpose except the ordinary crate put together with nails or screws, or cumbersome boxes or cases, in which the 20 machines are inclosed. It was the very urgent need of some more convenient and durable form of packing-case for shipping bicycles that led me to devise the collapsible or knock-down crate for this purpose which forms the 25 subject of my present application.

I am aware that in a broad sense such devices are not new with me. In other words, boxes, cases, and, in general, crates for protecting various articles in transportation by 30 steamer or railroad have been made in detachable or articulated sections, so as to be capable of being reduced, when not used for their intended purpose, to small compass. My invention, however, resides in the improvements which I have devised in a crate 35 more particularly adapted to receive a bicycle or similar machine and the novel structural features by which the greater efficacy, convenience, and economy of the device are seen.

40 The improvements are illustrated in the accompanying drawings.

Figure 1 is a side elevation of my device in condition for use. Fig. 2 is a similar view 45 showing the crate in a partially-collapsed condition. Fig. 3 is a detail of construction.

Fig. 1 represents the form of a completed 50 crate as it is usually constructed by nailing or screwing together pieces of wood. Considering such a crate as the device to which my improvements apply, I hinge together the four sides A B C D by the inside hinges a b

c d. I also divide the two sides of shorter length A B at or about their centers and hinge the two parts together by hinges e f. Next I 55 make the two cross-bars E F detachable from the sides, forming them with suitable clips or connecting devices, hereinafter described, and, finally, I make the diagonal braces G H detachable in the same manner as the cross-bars E F.

From the construction illustrated it will be seen that by detaching the cross-bars and braces the outer frame may be collapsed and packed into small compass, as indicated in 65 Fig. 2, and all the parts may be tied together in a compact bundle, to be restored at any time, without trouble or expense, to the condition of a complete crate.

As I understand the prior state of the art, 70 my improvement includes any means of attaching or connecting together the parts of the frame that will permit the frame parts to be folded or otherwise compacted, and with the result of making a rigid crate when expanded. I have, therefore, illustrated but 75 one way, the best now known to me of effecting this purpose.

To each end of the cross-bars or braces is 80 permanently secured a metal plate g. The end of the plate is bent at right angles at a point distant from the end of the wooden bar about equal to the thickness of the boards constituting the sides, and so as to make a tight-fitting union between the two. This union 85 is rendered more secure, however, by providing the under side of the metal plates, which are to a sufficient extent resilient, with projections which slip into corresponding indentations on the sides of the frame, as indicated 90 in Fig. 3.

The bicycle is packed for shipment in this 95 crate in the ordinary manner, the cross-bars taking the hubs, and the braces taking the saddle or saddle-post and the head, respectively, as indicated in Fig. 1.

Having now described my invention and illustrated the preferred manner in which the same is or may be carried out, what I claim is—

1. A collapsible crate for bicycles composed of a four-sided frame, the sides of which are jointed together at the corners, in combination with cross-bars E, F, detachably secured

upon either side of the shorter lengths A, B, at a point to support the bicycle and hold the frame in expanded position, as set forth.

2. A collapsible crate for bicycles having the four sides of the frame jointed together at the corners and at two opposite central points on its ends, in combination with cross-bars E, F, detachably secured upon either side of the ends A, B, at a point to support the bicycle, and detachable diagonal braces G, H, having one of their ends detachably secured to the side C and the other end similarly secured to the shorter end A, substantially as set forth.
- 15 3. A collapsible crate for bicycles composed of four-sided frame secured at the corners by

hinges, two of the opposite sides being also hinged at or near their centers, in combination with cross-bars E, F and the diagonal braces G, H, arranged to support the bicycle 20 when placed in the crate said cross-bars and braces being provided with catches for engaging with the sides and when in such engagement forming a rigid frame or crate for containing a bicycle in substantially the manner 25 herein set forth.

In testimony whereof I have hereunto set my hand this 3d day of September, 1895.

HERBERT G. STREAT.
